ROSCOE N. BAUGHN AND JOHN ELTON FULMER, OF CONWAY, ARKANSAS.

WIRING FOR IGNITION SYSTEMS.

Application filed March 2, 1922. Serial No. 540,478.

To all whom it may concern:

Be it known that we, ROSCOE N. BAUGHN and JOHN ELTON FULMER, citizens of the United States, residing at Conway, in the 5 county of Faulkner and State of Arkansas, have invented new and useful Improvements in Wiring for Ignition Systems, of which the following is a specification.

This invention relates to wiring for ignition systems, and one object is to provide for connecting the terminals at the coil box with the terminals of the timer by means of separate conductors which instead of being formed into a cable are separated or mounted in a particular manner, permitting individual wires to be renewed, and permitting any wire the insulation of which has become oil saturated, to be reversed end for end, so that the oil may be dried out over the engine.

A further object is to provide conductors having some distinguishing characteristic so that they may be correctly connected by an inexperienced individual, and to provide 25 clamping means for suspending wires from the radiator supporting rod of a Ford engine, and mounting means including a bracket adapted to be attached to the cylinder head, such brackets having connected therewith a clamp for retaining the wires in position as they pass to the timer, and holding them away from the fan and breather pipe.

With the foregoing and other objects in view, the invention consists in the novel construction and arrangement of elements described and claimed, it being understood that modifications may be made within the scope of the claim, without departing from 40 the spirit of the invention.

In the drawings, Figure 1 is a perspective view showing the means for retaining the conductors in position; Figure 2 is a perspective view of the bracket to be mounted 45 at the forward end of the engine, for supporting the wires out of the zone of intense heat, and for supporting clamp 31; Figures 3 and 4 are perspective views of the clamps, the elements of which are shown detached.

The wires 10, 11, 12 and 13 of some distinguishing characteristic, as previously intimated, and if desired the insulation may be differently colored. These wires are allowed to remain separated from each other,

that is they are not formed into a cable, but 55 are suitably retained or supported at intervals, in order that they may not be displaced.

The terminals of the coil box are designated 14, 15, 16 and 17, and the wires lead 60 to the terminals 18, 19, 20 and 21 of the timer 22. The radiator supporting rod 24 of a Ford engine is made use of for supporting a strap, or other device 26, by which the wires are held at a point adjacent to the 65 coil box.

A metallic bracket 27, of approximately the form shown, is secured to the cylinder head 28 by means of a bolt 29. This bracket includes a forwardly extending portion 30 70 on which a clamp 31 is mounted, being secured thereto by means of a bolt 33. This clamp serves to retain the wires, holding them away from the fan and other adjacent elements. Between this point and the timer 75 the wires may be drawn together and secured by means of tape 34.

In view of the arrangement specified, any one of the wires may be reversed end for end, or may be renewed, where under usual 80 circumstances the entire cable is renewed. It frequently happens that the end of the wire adjacent to the timer becomes saturated with oil, and by merely detaching this wire and placing the oil saturated end above the 85 engine and adjacent the coil box, the oil will be dried out. This operation may be repeated indefinitely, thereby making continuous use of the same wire or wires. However, owing to the position of the wires, as here 90 specified, the insulation will be maintained in good condition longer than if the wires are run along the lower parts of the engine frame. Obviously additional supporting means, of a similar character may be added 95 at any point desired, and similar minor changes may be made.

Having thus described our invention we claim:

Means for connecting a coil box and timer, 100 comprising a plurality of electrical conductors, having distinguishing characteristics, a bracket to be secured to a cylinder head and comprising an element extending forwardly from the cylinder head and an element extending upwardly from the head, 105 for holding the conductors in an approximately horizontal position, remote from the

zone of excessive heat, a clamp for securing the wires to the bracket and out of contact with adjacent elements of an engine, means for retaining the individual wires in proximity at a point between the clamp and the timer, and supporting means located between the bracket and the coil box and adapted for

connection with a radiator supporting element.

In testimony whereof we affix our signatures.

ROSCOE N. BAUGHN.
JOHN ELTON FULMER.
